UNITED STATES PATENT OFFICE

96,627

DESIGN FOR A SIPHON-BOTTLE HEAD

Harry J. Scott, San Francisco, Calif.

Application December 17, 1934, Serial No. 54,452

Term of patent 14 years

To all whom it may concern:

Be it known that I, Harry J. Scott, a citizen of the United States, residing at the city and county of San Francisco and State of California, have invented a new, original, and ornamental Design for a Siphon-Bottle Head, of which the following is a specification, reference being had to the accompanying drawing, forming a part thereof.

Fig. 1 is a side elevational view of the siphon-bottle head showing my design.

Fig. 2 is a plan view thereof.

I claim:

The ornamental design for a siphon-bottle head substantially as shown.

HARRY J. SCOTT.
